RAILWAY MOWER

Filed Dec. 1, 1927

Inventor
Ernest Sack, by

E. Kennedy
Attorney.

UNITED STATES PATENT OFFICE

ERNEST SACK, OF WAVERLY, IOWA

RAILWAY MOWER

Application filed December 1, 1927. Serial No. 237,037.

My invention relates to improvements in railway mowers, and the object of my improvements is to furnish a self-propelled device of this class, equipped with a laterally adjustable carriage supporting an upwardly swinging sickle, whereby a plurality of swaths may be cut alongside a railway track in succession and upon sloping surfaces.

This object I have accomplished by the means which are hereinafter described and claimed and which are illustrated in the accompanying drawing, which is a top plan of my improved railway mower, parts being broken away.

My invention is not restricted to the precise construction and arrangement of parts herein shown and described, nor to the various details thereof, as the same may be modified or rearranged in various particulars without departing from the spirit and scope of my invention, one practical embodiment of which has been herein illustrated and described without attempting to show all of the various forms and modifications in which my invention might be embodied.

My device includes a chassis or frame 1 similar to that of a passenger car, but may be differently shaped as desired. This chassis has a pair of spaced side bars supported in front on flanged car wheels 2, mounted to be dirigible and to be governed by a hand-wheel for steering. The rear wheels 3 are also of the flanged type to roll along the rails 4, and the forward and rear ends of the frame 1 are rigidly connected by the usual arched members as used in a car. An internal combustion engine 5 is mounted in the front part of the chassis and drives a rotary shaft 6 which by means of the usual differential gearing rotates the rear wheels 3.

A seat 7 is provided near the engine 5 for the convenience of a driver, another man being required to operate the mowing apparatus mounted upon said chassis.

The numeral 11 denotes an elongated or oblong frame having at opposite ends arched and rigid connecting members 13 and 14 respectively. Other arched members 15 are fastened rigidly across the bars 12 of frame 1 a little outside of the frame 11 in the posi-

tion of the frames 11 and 1 as shown. Longitudinal bars 16, 17 and 18 are end-connected to and across said arched intermediate located bars 15.

A sprocket-wheel 10 is secured upon the driving shaft 6 and has a rearwardly directed clutch-hub 9 with which mates teeth on a slidably non-rotatably splined clutch-sleeve 8 which is annularly grooved to seat a terminal fork on a pivoted arm mounted on an end of a hand-lever 20 which has a manually controlled detent engageable with teeth of a rack-sector 19 fixed on the bar 17, the lever being pivoted on the sector, and thus being operable to throw the clutch-sleeve in or out of engagement with said clutch-hub. A sprocket-chain 21 is positioned between the bars 11 longitudinally and engaged about the sprocket-wheel 10. Its left-hand end is carried around an idler sprocket 22 which is journaled in a forked member 23 whose stem is terminally threaded and seated in an apertured block or bearing element on the arched bar 13 and supplied with an adjusting nut 24 to take up slack in the chain. The opposite end of the chain 21 is passed around a sprocket-wheel 25 fixed on a counter-shaft whose ends are rotatable in bearings on short bars 45 connecting the spaced bars 44 and 14 which cross the right-hand end of the frame 11. An idler 46 is rotatably mounted in a bearing-box on the bar 16 over the upper reach of the chain 21 to bear against and taute it.

The numeral 31 denotes a sickle-bar having a reciprocable sickle device of a well-known type mounted upon it and has the usual end shoes at 29. The sickle has at the left a bar 27 rigidly connected thereto in alinement and having a crank-pin connection with a crank-pin on a disk-wheel 26 fixed on an end of the counter-shaft above referred to. Diverging arms 28 are fixed on the shoe 29 and have pivotal or hinging connections terminally with fixed pintles 43 on the end of the frame 11 at front and rear.

The sickle-bar 31 is swung up or down by following described means. The numeral 34 denotes an arm swingingly mounted upon the arch member 14, the latter having a link 33

and cable connection 32 to a short erect arm 30 fixed on the shoe 29. A cable 35 is end connected to the member 14 and has its other end connected to and to be wound upon a drum-shaft 37 which is rotatably mounted in bearings on the bars 12. The shaft 37 has at the rear a hand crank 41 and a ratchet wheel 47 thereon, the latter engageable by a gravity controlled pawl. A cable 39 is end connected to the front end of the shoe 29, thence passed forwardly obliquely about a sheave 40 on the forward right hand corner of the frame 1, thence rearwardly and about a sheave on said frame and then to the left and end-connected to a pulley 38 on the shaft 37 to be wound thereon. A third cable 42 is end connected to the arched member 13 and also end connected to the shaft 37 to be wound thereon.

20 The operator standing on the frame platform 11 may control the to and fro lateral movements of the frame 11 by rotating the crank 41 with the shaft 37 to wind the cables 35 and 42 reversely thereon, and thus the frame may be projected to the left from the position shown or after a cutting of a parallel outer swath. The sickle-bar 31 may be swingingly controlled by the arm or lever 34, the arm being left loose to let the shoes 29 ride upon the ground when mowing, or the arm 34 may be swung to erect the sickle-bar to clear whistle-posts in the way. The loosely swinging sickle-bar may react to avoid stones or small obstacles in the way by swinging a little over them upwardly.

25 The cable 39 cooperates with the cable 35 in the propelling of the frame 11 or returning of the same, and also in taking up side draft thrust, and the mounting of the frame 11 is such as also to almost entirely eliminate side draft thereon.

When parallel swaths have been cut alongside the rails 4 on one side of the right of way, and the chassis has been reversed in 30 direction at the end of its run, the other side of the right of way may be similarly mowed over. The arm 34 may be completely swung over to the left, erecting the sickle-bar 31 when not in use, and the arm then sprung into a hook 36 on the right-hand bar 15.

35 The lever 20 is used in the usual way in clutching the sleeve 8 to the hub of the sprocket-wheel 10 in causing rotation of the wheel and movement of the chain 21 in moving the frame 11 laterally to the right, the shaft 37 being used in returning it to the left.

Having described my invention, what I claim as new and desire to secure by letters 40 patent, is:

45 1. In combination, a wheeled chassis, mechanism mounted thereon for propelling it, an elongated frame movable across and upon said chassis to different positions of lateral adjustment, a sickle-device mounted

terminally upon said frame to be swung vertically, means for actuating the sickle of said device disconnectably operatively connected to said propelling mechanism, a cable connected to said sickle-device for eliminating side draft thereon, and a winding-drum 70 on said frame upon which the cable is windable.

2. In combination, a wheeled self-propelled chassis, a hingedly connected sickle-device and transversely mounted frame support therefor, the frame being mounted upon said chassis for lateral adjustments thereon to permit the sickle device to be projected laterally beyond the chassis to cut swaths at 75 different distances therefrom, and manually operable means for supporting movably the sickle-device relatively to said chassis to eliminate side draft thereon, consisting of a winding-drum on the frame, an idler pulley 80 in advance of the sickle-device on the forward part of the frame, and a cable windable upon said drum, reeved upon said pulley and end connected to the forward part of the sickle-device.

3. In combination, a wheeled chassis, a prime motor mounted thereon, an elongated frame movable across the chassis oppositely, a sickle-device mounted upon an end of the frame to swing vertically, disconnectible 95 means for actuating the sickle-device driven by the prime motor, means connected to said frame including a manually operable device for shifting it laterally oppositely, disconnectible connecting means between the prime motor and wheels of the chassis for rotating the wheels, a winding-drum on the frame, a cable connected to the sickle-device to prevent side-draft thereon, said cable being windable upon said drum, another cable windable on 100 said drum and connected to the sickle carrying end of the chassis, and a third cable wound reversely on said drum and end-connected to the opposite end of the chassis.

4. In combination, a wheeled chassis, a prime motor mounted thereon and disconnectibly connected to wheels of the chassis, an elongated frame mounted upon the chassis to shift across it laterally oppositely, a sickle-device mounted upon one end of the frame 110 to be adjustingly swung vertically, means disconnectibly connected between said prime motor and said sickle-device to operate the latter, manually operable means for shifting the frame to and fro laterally, and other means connected with said manually operable means and to said frame, a chassis and sickle device to assist in moving the frame in one direction and to resist side draft upon the sickle device.

115 In testimony whereof I affix my signature.
ERNEST SACK.
